8 Claims. (Cl. 240—41.25)

This invention relates to an adjustable electric lamp structure and, more particularly, to a miner's safety lamp of the type commonly referred to as a miner's cap lamp. In general, this form of lamp includes a headpiece in which an electric lamp is secured and means for supporting the headpiece on a cap, hat or other part of the clothing worn by a miner. An electric storage battery is supported by a suitable holding device around the waist of the miner and an electrical conductor extends from the battery upwardly to the headpiece.

Currently, miner's electric cap lamps are equipped with a reflector and two bulbs, or with a two-filament bulb. In the two-filament bulb, one filament is located at or near the focal point of the reflector and the other filament is located a short distance away from the focal point. Either filament provides a satisfactory light pattern when used with a matte-finished reflector, but only the filament most nearly in focus provides a satisfactory beam when used with a specular finished reflector of the class now employed most extensively in the art. More recent cap lamp models have included a focussing device to focus the more central filament but the second filament remains out of focus. Thus, the tendency has been for the miner to use the same focussed filament every day and to reserve the second filament for temporary and generally unsatisfactory use in the event of "burn-out" of the correctly focussed filament.

The present invention is based on the novel concept of combining filament energization and beam focussing in one simplified turning adjustment. To accomplish this objective, I have devised a lamp and electrical switch arrangement wherein I provide means responsive to movement of the electrical switch for focussing a reflected beam of light from the lamp.

The combined switch and focussing arrangement of the invention while adapted for use in focussing a light beam from either a single filament lamp or multiple filament lamp, is especially designed for use with a lamp having two filaments. The several components referred to are arranged in such relation to one another as to provide for sequential operation of each filament of a two-filament lamp whereby each filament is used interchangeably. Selective focussing of light from either filament takes place as a part of each sequence operation.

I have found that these concepts of sequential operation may be practically embodied on one form, in an adjusting lamp structure in which a unique rotor switch device is combined in interlocking relationship with a special lamp socket positioning apparatus. Both of these units are so designed and organized as to provide for a tightly sealed bulb and reflector arrangement and thus a high standard of safety and durability is insured.

An important feature of the invention is the construction of a rotor switch having a cylindrically shaped conductor body with which is combined a semi-circular insulating strip and a pair of spring contacts. By means of this arrangement rotative movement of the cylindrical switch body may be utilized to selectively open and close

independent circuits to each of the filaments in a two filament bulb.

Another important feature in the combination is the cylindrically shaped rotor of an eccentric device for actuating the lamp socket positioning apparatus so that the lamp may be located in a correctly focussed position regardless of which filament is energized.

These and other objects and novel features, will be more fully understood and appreciated from the following description of a preferred embodiment of the invention selected for purposes of illustration and shown in the accompanying drawings, in which:

Fig. 1 is a composite view in side elevation illustrating a lamp enclosure body for use with a miner's cap or other supporting means, and, further indicating a storage battery and an electrical conductor of the class commonly carried by a miner in conjunction with a miner's cap lamp;

Fig. 2 is a front elevational view of the lamp enclosure body shown in Fig. 1;

Fig. 3 is a cross-section taken on the line 3—3 of Fig. 2;

Fig. 4 is a cross-section taken on the line 4—4 of Fig. 2;

Fig. 5 is another cross-sectional view;

Fig. 6 is a detail elevational view of a focussing cam arrangement;

Fig. 7 is a detail plan view of hanger and bracket components showing the lamp socket removed;

Figs. 8-11 inclusive are diagrammatic views illustrating a series of sequence positions assumed by the rotor switch element and bulb positioning apparatus in operation; and

Fig. 12 is a detail perspective view.

Referring more in detail to the structure shown in the drawings, numeral 2 denotes a cup-shaped lamp enclosure body which may preferably consist of Bakelite or other rigid molded plastic. As shown in Figs. 1-3, the enclosure body is recessed at one side to define a chamber 4 which is normally closed by means of a glass lens 6 secured in place by means of a threaded bezel 8.

An electrical conductor cord 10 is connected through one side of the enclosure 2 and (at its opposite end) is connected to a storage battery 12 of the type utilized in conjunction with well-known charging devices. At the outer rear wall of the enclosure 2 is a clip element 14 for use in attaching the lamp structure to a supporting part of a miner's cap or the like, as suggested in Fig. 1.

The recessed portions of the enclosure 2 include shouldered sections 16 and 16' which are spaced apart to define a socket and bulb adjustment aperture 18, as shown in Fig. 4. Supported at the upper surfaces of the sections 16 and 16' are a pair of right angularly shaped hangers 20 and 20' which are pivotally mounted about slotted cam pins 22 and 22'.

The slotted cam pins 22 and 22' are constructed with intermediate cam portions 24 and 24' which engage in slots 26 and 26' located through the hanger elements 20 and 20' as suggested in Figure 7.

Supported in suspended relationship between the hangers on pivots 23 and 23' is a swivel bracket 25. It will be seen that the slotted cam pins 22 and 22' when turned will cause the cam portions 24 and 24' to move in the slots 26 and 26' and the bracket becomes swung into various positions of adjustment on the shouldered sections 16 and 16'.

The swivel bracket 25 is made up of two spaced apart sides as shown in Figs. 2 and 4 and projecting from these spaced apart sides is an extension arm 28. A lamp socket 30 of tubular construction is resiliently held on two opposite sides thereof by means of a pair of engaged springs 32 and 34 whose ends are anchored around a holding rod element 36 which is clearly shown in Figures 2 and 5. This holding rod element 36 also passes through openings

formed in upper extremities of the swivel bracket 25 and is movable with the bracket 25 when the slotted cam pins 22 and 22' are rotated.

Detachably secured in the socket 30 is a lamp 40 which is constructed with two filaments 41 and 42 as shown in Figure 3. The outer end of lamp 40 is engaged by a bulb holder 44 consisting of an eye portion and a retaining post which is rigidly fixed to the extension arm 28.

The bulb holder 44 functions to force the lamp against the resistance of the springs 32 and 34 and positions the end of the lamp against spring contact arms 46 and 48. The effect of this arrangement is to permit the lamp in the event it is broken, to be sprung ejected out of the socket by means of the tension in the springs 32 and 34, thus eliminating danger of igniting gases which may be present.

The spring contact arms 46 and 48 are so arranged as to provide electrical connections for independently energizing the two filaments 41 and 42. The circuits completed by these contact arms are under the control of a rotor switch 50 mounted inside the enclosure body as shown in Fig. 5. A knob 54 is fixed to the outer end of the spindle for externally operating the spindle and rotor switch.

At the inner end of the cylindrical switch portion 50 is secured an eccentric part 52 having fixed therein an actuating pin 54, which is arranged to extend through an elongated slot 56 formed in an angle piece 58 of the extension arm 28 as illustrated in Figures 3 and 4. By means of this arrangement it will be apparent that rotation of the rotor switch will act through the eccentric part 52 to oscillate the extension arm 28 and move the lamp socket and lamp through a short arc of travel. This arc of travel is so chosen as to provide for causing each of the two filaments 41 and 42 to move successively into respective true focal positions with respect to a parabolic reflector 7 supported by the shell #2 and fastened in place by the bezel ring 8.

It is pointed out that the arc of travel of the lamp produced by the eccentric movement described above occurs in a plane which lies substantially at right angles to the plane of the two paths of travel of the lamp induced by turning the two slotted cam pins 22 and 22'. Also, in both of these adjustments, the swivel bracket 25 is guided by a stud 60 fixed in one side of the enclosure body 2 as shown in Fig. 3 and projecting through a slotted end 62 of the arm 28. In the case of the two cam adjustments, the bracket rotates around the stud 60 as an axis; in the case of the eccentric switch adjustment, the bracket moves toward and away from the pin.

In accordance with the invention I further combine with the rotor eccentric part 52 means for alternately energizing the filaments 41 and 42 with each successive focussing adjustment. An important component in this connection is a semi-annular insulating strip 70 secured about the periphery of the eccentric 52 as indicated in Figs. 3 and 4 and shown in detail in Fig. 12. This insulating strip 70 is adapted to lie in rolling contact with the contact springs 46 and 48 as it is clearly shown in Fig. 3. It will be readily seen that as the eccentric part rotates, the spring 46 will be allowed to come into contact with the electrically conducting surface of the eccentric part 52, thus, completing a circuit to one of the lamp filaments. Further rotation of the eccentric part 52 will allow the contact spring 48 to come into contact with the electrically conducting surface, while at the same time, the contact spring 46 will be raised out of engagement with the conducting surface by means of the insulating strip.

The outer peripheral surface of rotor part 50 is also arranged to lie in wiping contact with a resilient brush element 50a extending from an electrical terminal T (Figs. 2 and 3). This brush element 50a is formed with a V-portion 50b for engaging in one or the other of two

V-slots as 50c to make an electrical connection and to also locate and define two off-positions.

An important feature of the invention is the arrangement of the insulating strip 70 in such relationship to the eccentric part 52 that as one of the filaments is turned into its true focal position, the insulating strip releases that contact spring which will energize a current through the filament thus focussed.

It will be observed that with an insulating strip of a size such that it extends through an arc of 180°, for example, there will be a short interval when both springs are out of contact with the conducting surface of the eccentric part and, thus, both filaments are held inoperative. Each filament circuit is thereafter energized in succession, during rotative movement of the eccentric part through an arc of approximately 180°.

Various operating positions of the rotor switch have been illustrated in Figs. 8-11 inclusive. Thus, in Fig. 8, the brush 50a is shown engaged with the rotor switch 50 in an off-position in which the insulating strip 70 is positioned to separate the two spring contacts 46 and 48 from the electrically conducting surface of the member 52. Thus, filaments 41 and 42 are both inoperative.

In Fig. 9, the rotor switch has been turned to a position in which the insulating strip 70 continues to hold contact spring 46 out of contact with the conducting surface of the member 52, but the spring contact 48 is in contact with the electrically conducting surface of member 52 and a circuit is closed through filament 41 which is grounded through the base of the lamp and back to a ground terminal as suggested by the conductor G in Fig. 2.

In Fig. 10, the brush 50a is again engaged with the rotor switch 50 to hold it in an off-position and both contact springs 46 and 48 are in an inoperative position.

In Fig. 11, spring contact 46 is in contact with the electrically conducting surface of member 52 while spring contact 48 is in an inoperative position and, thus, the circuit is closed through the filament 42 and grounded through the base and the electrical conductor G.

It is pointed out that by means of the bulb adjusting apparatus desired two entirely separate adjustments may be carried out. One adjustment is made at the time the bulb is installed in the lamp assembly. This adjustment is performed by a lamp maintenance man and is especially desirable in connecting bulbs manufactured with varying degrees of mis-alignment between the filaments and bulb axis, or varying length between the filaments and the bulb base pin. By moving one or the other or both of the slotted cam pins the bulb holder may be pivoted about either one of two axes and brought into a position where each filament may be accurately focussed depending on the position of the switch knob.

The second adjustment is of course designed to be carried out by a miner by turning the switch knob and essentially this adjustment is a means of periodically shifting from one filament to the other. It will be seen that the miner can thus renew the light beam in the event of sudden failure of one filament and he can do this in a convenient manner while the lamp is on the miner's cap.

Another advantage of the specific arrangement described is that instead of one filament being required to operate all of the time until failure, there will automatically occur an alternating type of operation since the rotor switch energizes first one and then the other filament. The net result of this may well be to realize longer operating life from a lamp before a bulb replacement operation is required. It will further be appreciated that the desirable two filament operation described is accomplished with both safety and durability being maintained.

The invention has been described in one preferred form in which a two filament rotor switch is combined with focussing position apparatus. It should be under-

stood that various changes and modifications may be resorted to in connection with this structural form of the invention and, similarly, I may desire to employ the combination rotor switch and focussing apparatus with various other filament arrangements, either of a single filament or a plurality of filaments in excess of the two illustrated.

The scope of the invention is to be understood as being defined by the appended claims.

Having thus described my invention, what I claim is:

1. A miner's lamp construction comprising in combination a lamp enclosure body, a lamp unit removably supported therein, said lamp unit including a lamp socket positioning mechanism and a tubular socket having a pair of electrical contact elements attached at either side thereof, a bulb member resiliently held in the socket and presenting a pair of filaments occurring in electrically connected relationship to the said electrical contact elements to constitute two independent sources through which current may flow, a storage battery and electrical conductor means leading therefrom, a manually operated rotary switch device for closing a circuit through one of said filaments and simultaneously opening a circuit through the remaining filament, a reflector mounted around the bulb in secured relationship to the enclosure body and having a bulb adjusting aperture formed therein, eccentric means forming a part of said manually operated rotary switch operatively connected to the lamp socket positioning mechanism, and said eccentric adapted upon movement of rotary switch device to pivot the socket and bulb and focus a reflected beam of light from whichever of the filaments is being energized.

2. Miner's lamp construction comprising in combination a lamp enclosure body, a lamp socket positioning mechanism including a lamp socket bracket, pivoted hanger elements for rotatively supporting the lamp socket bracket in suspended relationship in the enclosure body means for turning the pivoted hanger elements and lamp socket bracket through a predetermined arc of adjustment, extension arm means forming a part of the lamp socket bracket for pivoting the bracket in the hanger elements through a second arc of adjustment which lies in a plane at right angles to the said first part of adjustment, a tubular lamp socket received in the bracket, a lamp detachably mounted in the tubular socket, spring means for engaging a surface of the lamp and resiliently holding the lamp in the socket, said bulb presenting a pair of filaments and comprising two independent sources through which an electrical current may flow, a storage battery, an electrical conductor means for leading current to the filaments, a manually operated rotary switch device for closing a circuit through one of the said filaments and simultaneously opening a circuit through the remaining filament, a reflector mounted around the bulb in fixed relationship to the enclosure body and having a

bulb adjusting aperture formed therein, and means forming a part of said manually operated rotary switch for actuating said extension arm means on the lamp socket thereby to pivot the socket and bulb and focus a reflected beam of light in accordance with the filament which is being energized.

3. A structure according to claim 2 in which the means for actuating the extension arm means includes a rotor body having an insulating strip secured thereto.

4. In an electric lamp, an enclosure body, a reflector fixed in said enclosure body and having an apertured central portion, brackets fixed to each side of the enclosure body, a hanger structure including a lamp socket assembly pivotally mounted on said brackets for supporting a bulb for travel through the slot in the reflector, said bulb including filaments for independent illumination, circuit means for connecting a source of current with said filaments in said bulb for illuminating said filaments, switch means controlling said circuit means for selectively energizing said filaments, operating means connected to and actuated by said switch means, and means connecting said operating means and said pivoted hanger structure for swinging said bulb in an arc to selectively position said filaments in said bulb in predetermined focal positions with respect to said reflector simultaneously with the actuation of the switch means controlling the illumination of each of the filaments.

5. The structure of claim 4 characterized in that the brackets fixed to each side of the enclosure body are angularly adjustable.

6. The structure of claim 4 characterized in that the operating means connected to and actuated by the switch means comprise an eccentrically mounted member which travels in a slot formed in a portion of the hanger structure.

7. The structure of claim 4 characterized in that guide means are provided for maintaining the hanger structure in a defined arcuate movement.

8. Miners lamp construction comprising a source of illumination, manually operated rotary switch means for controlling operation of the source of illumination, means responsive to the rotary switch means for focussing a beam of light from said source of illumination when the switch means is actuated, said rotary switch means consisting of a rotor element, and said focussing means including a swivel bracket having a bulb supported therein, and mechanism for pivotally moving the bracket and bulb when the rotor element is rotated.
